UNITED STATES PATENT OFFICE.

SAMUEL M. STROOCK, OF PHILADELPHIA, PENNSYLVANIA, ASSIGNOR TO AUTOMATIC INVENTIONS COMPANY, A CORPORATION OF PENNSYLVANIA.

VENDING-MACHINE.

No. 910,156.

Specification of Letters Patent.

Patented Jan. 19, 1909.

Application filed March 5, 1907. Serial No. 860,675.

To all whom it may concern:

Be it known that I, SAMUEL M. STROOCK, a citizen of the United States, residing at Philadelphia, in the county of Philadelphia and State of Pennsylvania, have invented new and useful Improvements in Vending-Machines, of which the following is a specification.

This invention relates to a vending machine of that type provided with a plurality of magazine chutes for holding bottles of witch hazel, bay rum, containers for collar buttons, matches, confections and other articles for use at places of amusement, hotels, restaurants and other public places.

The invention has for one of its objects to improve and simplify the construction and operation of devices of this character so as to be comparatively easy and inexpensive to manufacture, composed of few parts, reliable and efficient in use and readily kept in order.

A further object of the invention is to provide a vending machine in which the operating parts are so arranged that the necessity of springs for restoring the mechanism to normal condition is eliminated, thus insuring the machine against derangement and getting out of repair.

Another object of the invention is to provide a push and pull device which operates in one direction through a coin to actuate the dispensing lever to enable the articles in the magazine tube to feed and which operates directly on the lever to discharge the lowermost article from the machine, the push and pull device insuring a positive actuation of the dispensing mechanism.

A still further object is the employment of a simple form of locking device so arranged as to automatically hold the dispensing lever against operation by the push and pull means except when a coin is dropped into the machine so that the push and pull means can operate through the coin to simultaneously release the locking device and actuate the dispensing lever.

Another object is the provision of a shutter arranged over each discharge opening of magazine chutes for preventing the forcible ejection of the articles from the chutes by the positive actuation of the dispensing levers.

With these objects in view and others, as will appear as the description proceeds, the

invention comprises the various novel features of construction and arrangement of parts which will be more fully described hereinafter and set forth with particularity in the appended claims.

In the accompanying drawings, which illustrate one of the embodiments of the invention, Figure 1 is a vertical section of the vending machine, showing the parts in normal position. Fig. 2 is a rear view of the machine with the back removed. Fig. 3 is a horizontal section on line 3—3, Fig. 1 and looking downwardly. Fig. 4 is a vertical section showing the dispensing lever of one of the magazines being actuated through the medium of a coin. Fig. 5 is a similar view showing the dispensing lever in one extreme position by full lines and the other extreme position for discharging an article by dotted lines. Fig. 6 is a perspective view of one of the shutters disposed over the discharge openings of the chutes.

Similar reference characters are employed to designate similar parts throughout the several views.

Referring to the drawing, A designates a box-like casing preferably formed with the ends and sides 1 and 2 integral with the front 3, and the back of the casing is closed by a back plate 4 that has a bottom plate 5 adapted to engage under the casing A, there being provided a suitable lock 6 for holding the back in position. The bolt 7 of the lock enters an opening in the top of the casing and co-operates with a dowel 8 on the bottom 5 of the casing that enters the bottom plate 5 for holding the casing and back together. The front 3 of the casing has one or more coin-receiving openings 9 and article discharging opening or openings 10. In the present instance, a vending machine is illustrated having three magazine chutes 11 that are formed by the sides 2 of the casing and a plurality of spaced partitions 12 extending rearwardly from the inner surface of the front 3, the chutes being open at the rear for permitting them to be recharged, and a cover or door 13 suspended on pintle lugs 14 is employed for closing the rear of the chutes. The chutes 11 have their walls converged at their lower ends so as to retain the articles in the chutes. The lower ends of the chutes are slotted from the front to the rear and movable back and forth in the slots 15 are dispensing levers 16 of the dis-

charging mechanisms. In order to prevent the articles from being forcibly ejected from the discharge openings 10, a shutter 16' is arranged over each opening so as to retard the movement of the article as it is ejected. Each shutter comprises a metal body hinged on a rod 17 at the upper front portion of the casing and supported on lugs 18 extending forwardly from the casing. The shutters 16 are all hinged on the rod or shaft 17 and they are free to swing outwardly at their lower ends. Each shutter has rearwardly extending longitudinal flanges 19, the lower ends of which are formed into lugs 20, as shown in Fig. 6, for preventing the article being discharged from dropping out laterally. The shutters are of sufficient weight that the articles are held in position by the shutters bearing on the outer ends thereof, when the articles are fully advanced by the dispensing levers, thus preventing the articles from dropping.

The dispensing levers 16 are fulcrumed at their lower ends on a shaft 21 supported in the sides 2 of the casing at the lower end thereof and these levers are held in alignment with their respective chutes 11 by spacing sleeves 22, on the shaft 21. The upper ends of the levers 16 are provided with forwardly extending heads 23 on which the articles in the chutes 11 are normally suspended and below the head 23 of each lever is a stop pin 24 arranged to engage the front of the casing to arrest the forward or ejecting movement of the lever. Extending laterally from one side of each lever is a lug 25 that cooperates with a coin-actuated locking device for holding the lever against actuation except when a coin is dropped into the machine. This locking device comprises a hook shaped detent 26 having a depending arm 27 arranged in the path of the coin employed to operate the dispensing lever associated with the locking device. The detents 26 of the several locking devices are fulcrumed on a horizontal shaft 28 supported on the sides 2 of the casing and disposed behind the coin-receiving openings 9. Extending across the back of the openings 9 is a horizontally extending plate 29 forming a guard for controlling the insertion of the coins into the machine.

The coin actuating means for the dispensing means and locking devices each comprises a pair of spaced rods 30 passing through openings in the front 3 of the casing and connected at their rear inner ends by a yoke 31 and at their forward ends by a grip or hand hold 32, and carried by the hand hold is a push finger or rod 33 that extends through an opening 34 in the casing front to engage an abutment 35 on the dispensing lever arranged in line with the actuating means. The abutment 35 of each dispensing lever is a hook-shaped projection between which and the adjacent push-finger 33 a coin is adapted

to enter to act as a medium through which the push finger actuates the companion dispensing lever in a rearward direction. The depending arm of each detent 26 is disposed at one side of and adjacent to the abutment 35 of the companion dispensing lever so that the coin for operating the lever serves as a key for operating the detent, the relative position of the coins to the levers and detents being clearly shown in Fig. 2. Arranged below each coin-receiving opening 9 are spaced projections 36 on the rear side of the front 3 which reserve the coins and whereby the latter are held in operative relation with the push fingers 33, abutments 35, and arms 27 of the detents. Each lever 16 extends between the rods 30 of the push and pull device for actuating the same and the yoke connected with each pair of rods serves to move the adjacent lever 16 forwardly for ejecting the articles from the chute. The push and pull devices thus serve by means of the central fingers 33, to swing the dispensing levers backwardly from under the columns of articles in the chutes so that the columns can move bodily downwardly for positioning the lowermost articles in line with the discharge openings and further serve by means of the yokes 31 to move the levers forwardly to eject the lowermost articles. The hand holds 32 of the push and pull devices are preferably castings having parallel sockets 38 into which the outer ends of the rods 30 and 33 are engaged, the castings being in the shape of the letter M, as shown in Fig. 3. The inner ends of the socketed arms 38 of the hand holds or grips are adapted to abut the front surface of the casing 3 and thus act as stops for limiting the inward movement of the individual push and pull devices and dispensing levers operated thereby.

From the foregoing description taken in connection with the accompanying drawings, the advantages of the constructions and of the method of operation will be readily apparent to those skilled in the art to which the invention appertains.

In operation, the vending machine is charged by first removing the casing A with the attached parts from the back 4 and then raising the chute cover 13 so that the individual chutes can be supplied with the articles, which, in the present instance, are represented as bottles. The casing and back are then put together and the machine is loaded for use. On the shutters 16 may be applied suitable words or advertising to indicate the articles contained in the chutes. A person desiring one of the articles, places a coin in the coin-receiving opening 9 below the chute in which the desired article is contained. This coin drops between the inner end of the push finger 33 below the said opening and the adjacent arm 27 of the locking device and abutment 35 of the dispensing

or ejecting lever 16. The person then pushes inwardly on the grip 32, thereby simultaneously causing the finger 33 to operate through the coin to release the locking device 5 and swing the lever 16 rearwardly from under the column of articles in the chute, whereupon the articles in the chute move downwardly to bring the lowermost one opposite the discharge opening thereof. The dispensing lever is now in the full line position shown in Fig. 5, and the coin has been dropped to the bottom of the casing. The grip 32 is then pulled forwardly to cause the lever whose head is engaged behind the 10 lowermost bottle, to move the said bottle outwardly through the opening 10, the bottle coming into engagement with the relatively heavy shutter which latter is moved to the dotted line position shown in Fig. 5 to serve 15 to hold the bottle from being thrown out during the forward movement of the dispensing lever. The grip 32 can be actuated by one hand by the operator, while the other hand is held under the discharge opening 10 20 to take the bottle after it has been ejected. During the forward movement of the lever 16, the lug 25 thereof engages the companion detent, whereby the latter is raised to interlock behind the said lug for the purpose of 25 preventing the dispensing lever from being pushed backwardly by any one attempting to operate the push and pull device without first putting a coin into the machine.

I have described the principle of operation of the invention, together with the apparatus which I now consider to be the best embodiment thereof, but I desire to have it understood that the apparatus shown is merely illustrative and that various changes 35 may be made when desired, as are within the scope of the claims.

Having thus described the invention, what I claim is:—

1. In an apparatus of the class described, 45 the combination of a casing, a chute therein for holding a plurality of articles, a member mounted to move back and forth to eject the lowermost article in the chute, a lock for holding the member in normal position, a 50 manually-actuated means arranged to directly engage and operate through a coin or equivalent device to engage the lock and simultaneously release the latter and move the member in one direction, and a manually-actuated means for positively moving the member in the opposite direction and causing the lock to automatically set.

2. In an apparatus of the class described, 60 the combination of a chute for holding a plurality of articles; a member for discharging the articles from the chute; a manually-actuated device for positively moving the member in both directions, said device comprising two parts, one for engaging the 65 member to move it in a direction to discharge

an article and the other arranged to operate through a coin to move the discharge member in the opposite direction, and a grip connected with both parts, and a locking device arranged to be released by one of the said 70 parts through the agency of the coin.

3. In an apparatus of the class described, the combination of a dispensing lever, a locking means arranged to normally hold the lever in locked position and adapt it to 75 be automatically released by engagement with a coin, and means for holding the coin in cooperative relation with the said locking means, with a manually-actuated device for moving the lever in both directions, said 80 device comprising separate members, and a grip connected with the members, one member being arranged to directly engage the lever for moving it in one direction and the other arranged to operate through the coin 85 to release the locking means and to move the lever in the other direction.

4. In an apparatus of the class described, the combination of a casing, an article-containing chute therein, a lever fulcrumed in 90 the casing and movable into and out of the chute for discharging articles therefrom, an abutment on the lever, a coin rest in the casing, and a locking means for the lever arranged adjacent the coin rest to be released 95 by the coin, with an actuator for the lever comprising a pair of parallel members extending into the casing, one member engaging behind the lever for moving it in a forward direction and the other member being 100 arranged to engage the coin and press the latter against the abutment and locking means to release the latter and move the lever rearwardly, and a grip secured to the outer ends of the members and holding the 105 latter in parallel relation.

5. In a coin controlled machine, a chute containing articles to be vended, a normally locked goods delivery lever working in the same to push the articles outward, and constructed and arranged to be moved directly by the coin, a swinging arm or bell crank to lock the said lever and the lower portion of which is adapted to be automatically held in normal position and to be also moved directly 110 by the coin to release the goods delivery lever and to move inwardly simultaneously with the said lever, and a manually-actuated device constructed and arranged to hold the coin against both the said arm and lever, 115 and to move the lower portion of all three parts inwardly, the manually actuated device being also adapted to control, and to loosely engage, the goods delivery lever, in order to drop the coin, upon being pulled outwardly, 120 before pulling the goods delivery lever back to its normal position.

6. In a coin controlled machine, a chute containing articles to be vended, a normally locked goods delivery lever working in the 125 130

same to push the articles outward consisting of a pivoted lever having a depending arm and constructed and arranged to be moved directly by the coin, a swinging arm or bell 5 crank to lock the said lever and pivoted intermediate the ends of the said lever, and having a depending arm lying a little in advance or forward of the first named depending arm, and constructed and arranged 10 to be automatically held in normal position, and to be also moved directly by the coin to release the goods delivery lever, and the lower portion of which is adapted to move inwardly simultaneously with the said lever, 15 and a manually-actuated device consisting of a horizontally movable structure having

wires or arms constructed and arranged to hold the coin against the said depending arms, and to move the lower portion of all three parts inwardly simultaneously, the 20 manually-actuated device being also adapted to control, and to loosely engage, the goods delivery lever, in order to drop the coin, upon being pulled outwardly, before pulling the goods delivery lever back to its normal 25 position.

In testimony whereof, I affix my signature in presence of two witnesses.

SAMUEL M. STROOCK.
